UNITED STATES PATENT OFFICE.

ESMOND M. SMITH, OF NEW YORK, N. Y., ASSIGNOR OF ONE-HALF TO LEOPOLD PLAUT
AND ONE-HALF TO HERMAN PLAUT, BOTH OF NEW YORK, N. Y.

LIGHTING-FIXTURE.

1,248,187.

Specification of Letters Patent. Patented Nov. 27, 1917.

Application filed January 29, 1917. Serial No. 143,475.

To all whom it may concern:

Be it known that I, ESMOND M. SMITH, a citizen of the United States, and a resident of the city, county, and State of New York, (formerly of Chicago, Illinois,) have invented a certain new and useful Lighting-Fixture, of which the following is a specification.

My invention relates to lighting fixtures and more particularly to devices used in indirect and semi-indirect illumination in which an opaque or translucent globe or bowl is suspended below a reflector in such a manner that the direct rays of light are prevented from reaching the eyes of the observer and in which no shadows of intervening objects will be cast upon the reflector, or upon the ceiling if a reflector be not employed.

The object of my invention is to produce a lighting fixture having a globe bowl supported below a ceiling or other reflecting surface in such a manner that the supporting means are inconspicuous.

A further object is to provide means whereby the globe or bowl may be easily applied to or removed from the fixture by means which are located outside of the fixture.

These and further objects will more fully appear in the following specification and accompanying drawings considered together or separately.

I have illustrated one embodiment of my invention in the accompanying drawings in which like parts are designated by similar reference characters in all of the figures, and in which—

Figure 1 is a sectional view of a lighting fixture embodying my invention.

Fig. 2 is a detail sectional view of the support guide-thimble, the section being taken on the line indicated by 2—2 in Fig. 1.

Fig. 3 is a similar view of the support locking-sleeve, the section being taken at the point of the greatest diameter of the sleeve.

Fig. 4 is a top plan view of the shade supporting shell, and Fig. 5 is a detail view of a modification.

In carrying out my invention I provide a base 1 secured to the ceiling 2 and covering a junction box 3. In the embodiment of the invention illustrated this base is formed of sheet metal and of conical form.

To the lower extremity of the base is se-

cured by screws 4 or otherwise a thimble 5. The lower extremity of the thimble is closed by means of a plate 6 and an outwardly extending peripheral flange 7 extends around the lower edge of the thimble. The flange 7 is provided with a plurality of radial slots 8, three being shown. The body of the thimble is perforated at 9. The perforations are three in number and each is in vertical alinement with a slot 8. In each perforation 9 the hooked end of a spring arm 10 engages. The arms extend vertically downward and pass through the guide slots 8. The arms are then curved outward and their free ends terminate in hooks which engage a head or flange 11 on the upper edge of a globe or bowl 12.

Secured to the upper part of the thimble 5 by means of a bayonet joint 13 is a shell 14 in the lower end of which a reflector or artificial ceiling 15 is secured by means of screws 16 or otherwise.

A locking sleeve 17 surrounds the timble 5 and is rotatable relatively thereto. The sleeve is secured in place by means of a bead 18 turned over the periphery of the flange 7. A plurality of cams 18^a, one for each spring arm 10 is carried by the lower end of the locking sleeve and one disposed below the plate 6 and flange 7. The cams contact with the spring arms and secure them against spreading. One of the cams is provided with a notch 19 near its high part. The upper extremity of the sleeve 17 is provided with two fingers 20, which project through slots 21 in the shell 14. The fingers 20 are accessible from outside of the fixture and the sleeve may be rotated and the arms 10 may be adjusted to be engaged with or disengaged from the bowl 12 with rapidity and ease and without dismantling the structure.

Secured within the lower extremity of the base 1 above the thimble 5 is a ring 22 to which is secured a socket. The socket is composed of two parts 23 and 24 secured together by means of screws 25 or otherwise. The upper part of the section 23 of the socket is reduced in diameter and this reduced portion forms, when the two parts are secured together, a circumferential groove 26 with which the ring 22 engages and supports the socket. A lighting element 27 is secured in the socket in the usual manner.

The bowl or globe is so positioned rela-

tively to the reflector 15 and lamp 27 that all of the rays of light reflected from the concave upper surface of the bowl together with rays of light from the lamp which have 5 not been so reflected will be cast on the lower surface of the reflector 15, and thence reflected into the room or other space to be illuminated. The concave surface of the bowl is rendered diffusive by having its 10 reflective surface broken up by means of ribs or corrugations, or by sand blasting or acid etching, and the diffused light reflected from the bowl will scatter and disperse the shadows of the arms 10 and no shadows or 15 halations will be cast upon the surface of the reflector 15.

For indirect lighting the outer surface of the bowl may be silvered and the silver protected by paint or other suitable covering. 20 For semi-indirect lighting the bowl is translucent so that some of the light may pass through it and be diffused.

The spring supporting arms are given a 25 reverse curve relatively to the curves of the bowl so that when the fixture is viewed from the floor they will be hidden by the edge of the bowl which will appear to be freely suspended in the air. The arms are fashioned of thin spring metal so that the shadows cast 30 by them will be insignificant and easily dispersed by the diffused rays from the bowl and reflector.

The spring arms are under a tension which 35 normally causes them to spring outwardly. This tendency is resisted by the cams 18. When the sleeve 17 is rotated in the clockwise direction the cams will force the arms inward and the hooks on the free ends thereof will engage the flange on the bowl and the 40 arms will be held in that position. When the arms are locked in engagement with the bowl, one of the arms will engage the notch 19 and prevent accidental rotation of the sleeve. When it is desired to release the 45 bowl from the arms considerable force will be required to rotate the sleeve to release the arm from the notch. The sleeve may now be rotated in the anti clock-wise direction and the natural spring of the arms will release the hooks at their ends from the flange 50 of the bowl.

The bottom plate 6 is treated in the same manner as is the surface of the reflector whereby the reflector will appear to have a 55 continuous surface broken only by the thin wire arms and the stem of the lamp.

Instead of the open cams 18^a the locking sleeve 17 may be provided with a bottom flange member 28 which is provided with 60 cam slots 29 corresponding to the cams 18^a. The spring arms 10 pass through the slots 29 and the arms may be moved toward or away from the center of the sleeve as the latter is rotated in one direction or the other. 65 One of the slots is provided with a jig car-

rying a notch similar to the notch 19 and for the same purpose.

In accordance with the provisions of the patent statutes I have described the principle of my invention, together with the apparatus which I now consider to represent the best embodiment thereof, but I desire to have it understood that the apparatus shown is merely illustrative, and that the invention may be carried out in other ways. 70

Having thus described my invention what I now claim and desire to secure by Letters Patent, is:

1. A lighting fixture having a support, a lighting element, a globe or bowl surrounding the element, a member carried by the support, arms carried by the member and supporting the globe or bowl, a reflector supported by the member in opposed relation to the globe or bowl, said member having a reflecting surface in line with said reflector. 80

2. A lighting fixture having a support, a lighting element, a globe or bowl surrounding the element, a member carried by the support, arms carried by the member and supporting the globe or bowl, an annular reflector supported by the member in opposed relation to the globe or bowl, said member having a reflecting surface filling the space in said reflector. 90

3. A lighting fixture having a support, a lighting element, a globe or bowl surrounding the element, a cylindrical member carried by the support, a shell removably secured to the member, and a reflector carried 100 by the shell, the said reflector having an opening therein, the bottom of the member being approximately in line with said reflector and closing the opening whereby the reflecting surface will be uninterrupted. 105

4. A lighting fixture, having a support, a lighting element, a globe or bowl inclosing the element, a thimble carried by the support, a plurality of filamentous spring arms carried by the thimble, a flange on the 110 thimble, there being a slot in the flange for the reception of each arm, a sleeve supported on the flange, a cam carried by the sleeve, for engagement with each arm, a notch in a cam, and means for rotating the sleeve to 115 engage the arms with the bowl to support the same, a shell surrounding the sleeve, said rotating means extending through the shell, and a reflector carried by the shell, the thimble having a bottom forming a reflecting surface, and means for removably securing the shell to the thimble. 120

5. A lighting fixture, having a support, a lighting element, a globe or bowl inclosing the element, a thimble carried by the support, a plurality of filamentous arms carried by the thimble, a flange on the thimble, there being a slot in the flange for the reception of each arm, a sleeve supported on the flange, a 125 flange on the sleeve, there being a cam slot 130

in the flange on the sleeve, for engagement with each arm, there being a notch in a slot for engagement with an arm, and means for rotating the sleeve to engage the arms with the bowl to support the same, a shell surrounding the sleeve, said rotating means extending through the shell, a reflector carried by the shell, the thimble having a bottom forming a reflecting surface, and means for removably securing the shell to the thimble. 10

This specification signed and witnessed this twelfth day of January, 1917.
